[57] CLAIM

The ornamental design for a side pocket for a handbag or the like, as shown and described.

DESCRIPTION

FIG. 1 is a perspective view of a side pocket for a handbag or the like showing my new design;

FIG. 2 is a right side elevational view;

FIG. 3 is a perspective view thereof with the main flap in an open condition; and,

FIG. 4 is a perspective view thereof showing the interior pockets in open condition.

The side opposite that shown in FIG. 1 is substantially plain.
